UNITED STATES PATENT OFFICE

ROWLAND SPENCER, OF ST. ANNES-ON-SEA, ENGLAND

MULTIPLE-PLY WOVEN FABRIC

Application filed May 10, 1928, Serial No. 276,743, and in Great Britain June 27, 1927.

The present invention relates to an improved multiple ply woven fabric.

The present invention is particularly suitable for use as a covering for drying cylinders 5 of paper making machines, since it is possible thus to produce a material having a coated surface and a cotton internal structure. That is, the material has both the absorptive property of the worsted in its presentation against 10 the wet sheet, and also the resistance of the worsted animal fibre with respect to the acid which is usually present in the paper web. The vegetable fibre such as cotton employed on the interior, however, is of much greater 15 tensile strength and is much less expensive than worsted, although less absorptive, and less adapted to yield off its moisture rapidly.

According to the present invention a textile fabric is formed of multiple ply construction composed partly of doubled cotton yarns and partly of cotton and worsted 20 yarns doubled together.

The invention is more particularly described with reference to the accompanying 25 drawing showing in section one preferred arrangement of multiple ply cloth.

The diagram shows a four ply cloth formed of weft 1, 2, 3, 4, of doubled worsted and cotton. Each line of warp as will be noticed, 30 binds the weft of two adjacent lines. The warp threads 5, 6, 7, of the three lower plies are of doubled cotton, whilst the warp 8 of the upper ply is of doubled worsted and cotton. This outer ply will therefore, form the 35 surface layer and will form a fabric particularly suitable as a cover for the drying cylinders of paper making machines.

Instead of making the wefts 2, 3, 4, of doubled worsted and cotton, these or certain 40 of them may be either simply cotton and worsted or cotton.

I declare that what I claim is:—

A multiple ply cloth adapted to form a cover for the drying cylinder of a paper-making machine composed of weft of dou-

bled cotton and worsted, the outer ply having a warp of doubled cotton and worsted, the warps of other plies being of doubled cotton.

In witness whereof, I have hereunto signed 50 my name this 26th day of April, 1928.

ROWLAND SPENCER.
